US00D851585S

(12) **United States Design Patent** (10) Patent No.: **US D851,585 S**
(45) Date of Patent: **** Jun. 18, 2019**

(54) **BATTERY CHARGER**

(71) Applicant: **SZ DJI Technology Co., Ltd.**,
Shenzhen (CN)

(72) Inventors: **Tao Zhao**, Shenzhen (CN); **Kenan Li**,
Shenzhen (CN); **Yun Zhao**, Shenzhen
(CN)

(73) Assignee: **SZ DJI Technology Co., Ltd.**,
Shenzhen (CN)

(**) Term: **15 Years**

(21) Appl. No.: **29/639,933**

(22) Filed: **Mar. 9, 2018**

Related U.S. Application Data

(63) Continuation of application No. 29/579,395, filed on
Sep. 29, 2016, now Pat. No. Des. 815,034.

(57) **CLAIM**

The ornamental design for a battery charger, as shown and
described.

DESCRIPTION

FIG. 1 is a top front perspective view of a battery charger
showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top front perspective view thereof in an environment
in which it may be used.

The broken lines in the figures show portions of the battery
charger and environment that form no part of the claimed
design.

1 Claim, 6 Drawing Sheets
